US00D613868S

(12) **United States Design Patent**
Lhuillery et al.

(10) **Patent No.:** **US D613,868 S**
(45) **Date of Patent:** **** Apr. 13, 2010**

(54) **TRANSCUTANEOUS ELECTRICAL NEURAL STIMULATION DEVICE**

(75) Inventors: **David Lhuillery**, London (GB); **Andrew Clift**, London (GB)

(73) Assignee: **Kinetik Medical Devices Ltd.**, Kowloon (HK)

(**) Term: **14 Years**

(21) Appl. No.: **29/319,247**

(22) Filed: **Jun. 5, 2008**

(30) **Foreign Application Priority Data**

Dec. 7, 2007 (GB) 4005564

(51) **LOC (9) Cl.** **24-01**

(52) **U.S. Cl.** **D24/187; D24/155**

(58) **Field of Classification Search** D24/144, D24/158, 164, 167, 168, 170, 187, 200, 231; 600/300, 301, 368, 372, 481, 529, 544, 554, 600/561; 607/4, 5, 9, 30

See application file for complete search history.

(57) **CLAIM**

The ornamental design for a transcutaneous electrical neural stimulation device, as shown and described.

DESCRIPTION

FIG. 1 is a top perspective view of a transcutaneous electrical neural stimulation device showing our new design;

FIG. 2 is a rear perspective view thereof;

FIG. 3 is a top plan view thereof;

FIG. 4 is a bottom plan view thereof;

FIG. 5 is a front elevation view thereof, the rear elevation view being a mirror image of FIG. 5; and,

FIG. 6 is a left elevation view thereof.
